UNITED STATES PATENT OFFICE.

FRANK A. RYTHON, OF CHICAGO, ILLINOIS, ASSIGNOR TO DEERING HARVESTER COMPANY, OF CHICAGO, ILLINOIS.

HARVESTING-MACHINE.

SPECIFICATION forming part of Letters Patent No. 720,624, dated February 17, 1903.

Application filed November 13, 1902. Serial No. 131,108. (No model.)

To all whom it may concern:

Be it known that I, FRANK A. RYTHON, a citizen of the United States, residing at Chicago, in the county of Cook and State of Illinois, have invented a new and useful Improvement 5 in Harvesting-Machines, of which the following is a specification.

The object of my invention is to provide an improved driving-roller for the platform-conveyer of a harvesting-machine, whereby the following desirable qualities are obtained: First, a narrow or shallow platform, thus permitting of short-cutting; second, a lowering of the platform-conveyer relative to the knife 15 of the cutting apparatus, which will thus more readily allow short grain or grass to be delivered upon said platform without clogging on the finger-bar; third, the advantages of a platform-driving roller whose ends are 20 of a smaller diameter than the intermediate portion thereof and which still has the outer elements or those elements on the stubble side of the inner roller lying in the plane of the axes of the two platform-rollers parallel 25 with the axes thereof, thus allowing the said platform-conveyer to be placed near the elevator-conveyers and also avoiding the stretching of the center of the platform-conveyer in excess of that of the ends.

Figure 1 is a fragmentary perspective of a portion of a harvester embodying my invention. Fig. 2 is a sectional view taken as indicated in Fig. 1, showing the roller, canvas, and section of platform. Fig. 3 is a fragmentary plan and section showing my improved roller and adjacent parts. Fig. 4 is a sectional view of the roller.

Referring to the drawings, A represents a portion of the A-frame of a harvester; B, the 40 cutting apparatus; C, the platform; D, the endless platform-conveyer, and E the two-piece inner platform-conveyer roller. The novel construction and arrangement of this roller constitute my invention.

45 c and c' are the front and rear platform-slides, respectively, which are secured to the front and rear bars of the platform C.

The roller E virtually consists of two frusta of cones made hollow, their larger bases abut-

ting and adapted to receive longitudinally a 50 loosely-fitting square shaft e, the ends e' of which are cylindrical and journal in the slides c c. On the cylindrical portion e' of the rear end of the shaft e is secured the sprocket-wheel e², which drives the shaft e and roller 55 E thereon. The smaller diameters of the rollers E are formed with square apertures centrally located and continuous with the internal cavity of the said hollow rollers, the said apertures being slightly larger than the 60 square shaft which passes therethrough in order to permit the roller to rotate with its interior contacting constantly the square shaft in the same position relative to the shaft, the roller and the endless conveyer passing over 65 the said roller. The rear end of the roller E is raised, as shown in Fig. 2, so that the lower elements of the forward cone will be substantially parallel with the bottom of the platform; and thus leave clearance for the end- 70 less conveyer to pass between.

What I claim as my invention, and desire to secure by Letters Patent, is—

1. In a harvester, in combination with a grain-receiving platform, a cutting apparatus 75 and an endless conveyer, a two-part driving-roller, consisting of two conical frusta, the larger bases thereof adjacent, and the geometric axes of the two parts thereof being at a sufficient angle with the line of advance of 80 the machine to bring the stubble side of the said two-part roller approximately parallel with the said line of advance, substantially as described.

2. In a harvester, in combination with a 85 grain-receiving platform, a cutting apparatus and an endless conveyer, a two-part driving-roller consisting of two hollow conical frusta, their larger bases abutting and the geometric axes thereof being at a sufficient angle with 90 the driving-axis of said two-part roller to bring the stubble side thereof approximately parallel with the said driving-axis, and means for supporting and driving said hollow conical frusta, substantially as described. 95

3. In a harvester, in combination with a grain-receiving platform, a cutting apparatus and an endless conveyer, a two-part driving-

roller consisting of two hollow conical frusta, their larger bases abutting and the geometric axes thereof being at a sufficient angle with the driving-axis of said two-part roller to bring the stubble side thereof approximately parallel with the said driving-axis, and a

square shaft adapted to support and drive the said two hollow conical frusta, substantially as described.

FRANK A. RYTHEW.
